United States Patent Office

Des. 234,034
Patented Jan. 7, 1975

234,034

CHAIR

Jerry Johnson, Rancho Cuello, Box 50,
Portrero, Calif. 92063

Filed May 10, 1973, Ser. No. 359,007

Term of patent 14 years

Int. Cl. D6—01

U.S. Cl. D6—56

FIG. 1

FIG. 2

FIG. 3

FIG. 4

FIG. 5

FIG. 1 is a perspective view of a chair showing my new design;

FIG. 2 is a side elevational view showing the side not visible in FIG. 1 thereof;

FIG. 3 is a rear elevational view thereof;

FIG. 4 is a top plan view thereof; and

FIG. 5 is a bottom plan view thereof.

I claim:

The ornamental design for a chair, substantially as shown.
